E. E. WINKLEY

AUTOMATIC STEERING APPARATUS

Original Filed May 8, 1918

UNITED STATES PATENT OFFICE.

ERASTUS E. WINKLEY, OF LYNN, MASSACHUSETTS.

AUTOMATIC STEERING APPARATUS.

Application filed May 8, 1916, Serial No. 233,280. Renewed May 17, 1922. Serial No. 561,714.

To all whom it may concern:

Be it known that I, ERASTUS E. WINKLEY, a citizen of the United States, residing at Lynn, in the county of Essex and State of Massachusetts, have invented certain new and useful Improvements in Automatic Steering Apparatus; and I do hereby declare the following to be a full, clear, and exact description of the invention, such as 10 will enable others skilled in the art to which it appertains to make and use the same.

The present invention relates to an improvement in automatic-steering apparatus.

The object of the invention is to produce 15 an automatic steering apparatus of such construction and arrangement of parts that the vehicle to which it is applied will be directed or guided to a predetermined level or horizontal plane of travel either above or below 20 the starting level and will thereafter be maintained on the plane of travel at the predetermined level. The guiding-device of the vehicle may be any suitably arranged rudder or equivalent device which, according 25 to its position, causes the vehicle to ascend, descend or be maintained on a predetermined plane of travel. For the purpose of moving the guiding-device to cause the vehicle to proceed to the predetermined 30 level or plane of travel, the steering apparatus of the present invention is preferably provided with means which are thrown into operation to act upon the guiding-device when the vehicle has reached a predetermined 35 speed on one plane of travel. When the vehicle has attained the predetermined level, other means with which the steering apparatus is provided are thrown into operation to act upon the guiding-device to 40 maintain the vehicle on the plane of travel at the predetermined level. The present invention consists in the structure particularly pointed out in the appended claims, a specific embodiment of this structure being 45 described in the following specification.

The preferred form, in which it is at present contemplated embodying the invention, is illustrated in the accompanying drawings, in which Figure 1 is a front elevation, partly 50 in section, of the improved steering apparatus, showing its application to an aerial vehicle; Fig. 2 is a sectional elevation on the line 2—2, looking in the direction of the arrow; and Fig. 3 is a plan of the rack and 55 pawl device.

For convenience of illustration and de-

scription, the improved steering apparatus of the present invention is shown in the drawings as applied to a flying machine. The guiding-device which, according to its 60 position, causes the flying machine to ascend, descend or be maintained on a predetermined plane of flight or travel, may be of any usual or preferred construction and so it need not be shown in the drawings. This guiding-device may be the sustaining wing planes of the flying machine; it may be the elevator, the ailerons or the horizontally arranged rudder. The movements of this guiding-device are controlled in the illustrated embodiment of the invention by centering cam 65 5 mounted to slide forwardly and rearwardly on a horizontal shaft 6 arranged to extend in a fore and aft direction. The construction and arrangement of the connections between the centering cam 5 and the guiding-device which, for convenience, will hereinafter be termed the "wing planes" of the flying machine may conveniently be the same as the construction and arrangement of 70 the connections between a correspondingly positioned centering cam and the sustaining wing planes of the flying machine illustrated and described in the patent to Winkley, 1,200,288, granted October 3, 1916. A 75 movement of the centering cam rearwardly, viewing Fig. 1, that is to the right, viewing Fig. 2, will, as in the flying machine illustrated in the said patent, turn the wing planes to be presented at a greater angle of 80 incidence to the atmosphere so as to cause the flying machine to ascend and, conversely, a movement of the centering cam forwardly, that is to the left, viewing Fig. 2, will turn the wing planes to be presented at a lesser 85 angle of incidence to the atmosphere so as to cause the flying machine to descend.

The forward and rearward movements are imparted to the centering cam 5 by means of a roll 7 received in a groove 8 formed on 100 the forward end of the cam 5. The roll 7 is carried by the upper end of an arm 9 loosely mounted on a shaft 10, journaled in a framework 11 secured to or forming part of the framework 12 for supporting the propelling 105 means of the flying machine to which the steering apparatus is applied. Secured to the arm 9 by means of a rod 14 is a lever 15 also loosely mounted on the shaft 10. The lever 15 is provided with an enlarged hub 110 16, projecting radially from which is a pin 17 loosely received in a cam slot 18 formed

in the recessed head 20 of a sleeve 21 slid-
ingly mounted on the shaft 10, and con-
nected with the shaft 10 by a spline and slot
so as to turn therewith. The recess in the
5 head 20 of the sleeve 21 is of such size that
the head slides over the hub 16 of the lever
15 when horizontal movements are imparted
to the sleeve 21 by means of a roll 24 loosely
received in a groove 25 in the sleeve. The
10 roll 24 is carried on the upper end of the
vertically arranged arm of a bellcrank lever
26 pivoted on the frame of the flying
machine. When the sleeve 21 is moved to the
15 left, viewing Fig. 1, the lever 15 is turned
in a clockwise direction so as to move the
centering cam 5 rearwardly and thereby tilt
the wing planes of the flying machine to a
greater angle of incidence, so as to cause the
20 machine to rise; and when after the sleeve
21 has been moved to the left, it is again
moved to the right, the lever 15 is turned in
a contra-clockwise direction so as to move
the centering cam 5 forwardly and thereby
25 tilt the wing planes so as to present a lesser
angle of incidence and thereby cause the
flying machine to descend. When the parts
just described are in the condition shown in
Fig. 1, the sustaining wing planes of the
30 flying machine are in horizontal position.
This will be the condition of the parts when
the machine is running on the ground pre-
paratory to rising.
The bellcrank lever is actuated by a spring
27 to move the collar 21 to the left, viewing
35 Fig. 1, when the cam roll 29 carried by
the free end of the horizontally arranged arm
30 of the lever 26 is received in the depres-
sion 32 of a cam 33 secured to a shaft 34
mounted to slide but not turn in brackets 35
40 and 36. The shaft 34 is moved to bring the
cam depression 32 opposite the roll 29, by
means of a centrifugal device, generally in-
dicated by the reference character 38. This
45 centrifugal device comprises obliquely posi-
tioned arms 39 carrying weights 40 on their
outer ends. The arms are normally drawn
toward each other by means of a spring 41.
The centrifugal device 38 is connected by
50 links 42 with a head 43 mounted to slide on
the right-hand end of the shaft 34. The
head 43 moves the shaft 34 by engagement
with a collar 37 secured on the end of the
shaft. The arms 39 of the centrifugal de-
55 vice are pivotally mounted at 44 on the end
of a shaft 45 journaled in the lower ends of
arms 46 depending from a bracket 47 se-
cured to the frame 11. The shaft 45 carries
a bevel gear 48 which meshes with a corre-
60 sponding bevel gear secured to the upper
end of a vertically arranged shaft 49. The
shaft 49 is connected by the bevel gears 50
with a horizontally arranged shaft 51, in
turn connected by the bevel gears 52 with a
65 vertically arranged shaft 53 connected by
the bevel gears 54 with the axle 55, upon
which the wheels 56 of the flying machine
are mounted. When the flying machine is
started in flight, the contact of the wheels 56
70 with the ground rotates the axle 55. The
rotation of the axle 55 is communicated to
the shaft 45 so as to turn the centrifugal
device 38. When the flying machine reaches
a certain speed on the ground, the centri-
75 fugal force acting upon the weights 40 throws
them outwardly and thereby pulls the shaft
34 to the right through the engagement of
the head 43 with the collar 37. When a pre-
determined speed is reached, the weights 40
80 are such distance apart that the depression
32 is moved opposite the roll 29, and there-
upon the spring 27 by pulling the roll 29
into the depression 32, acts to move the collar
21 to the left, so as to turn the lever 15 in
85 a clockwise direction to move the centering
cam 5 rearwardly and thereby tilt the wing
planes of the flying machine to present them
at an angle of incidence to the atmosphere,
so as to cause the flying machine to rise.
Stop arms 58 are provided so that the cen-
90 trifugal action upon the device 38 will not
move the shaft sufficiently far to the right
to carry the depression 32 beyond the roll
29. When the machine leaves the ground,
the wheels 56 will of course no longer ro-
95 late, and so the arms 39 of the centrifugal
device will be pulled toward each other by
the spring 41, the head 43 sliding on the
shaft 34 without disturbing its position.
When the shaft 34 has been moved by the
100 travel of the flying machine upon the ground
so as to tilt the wing planes to cause the
machine to rise, the machine continues to
rise until it reaches a predetermined
height, whereupon the steering apparatus
105 acts to decrease the angle of incidence of the
wing planes to a predetermined angle to
keep the flying machine at the predetermined
height or plane of travel. This is effected
110 by means of a pawl and rack device
generally indicated at 58 which operates to
cause the shaft 34 to move to the right so as
to force the roll 29 up the incline 60 and
onto the surface 61 of the cam 33. This
115 pawl and rack device 58 comprises two
pawl's 63 and 64 which are normally held
from engagement with a rack 65, fixed on
the shaft 34, by means of the springs 66 and
67 respectively. The pawl 63 acts as a de-
120 tent to prevent retrograde movement of the
shaft 34; and the pawl 64 acts as an actua-
tor to rack the shaft 34 to the right to force
the roll 29 out of the depression 32 and onto
the surface 61. For this latter purpose the
pawl 64 is pivoted on the upper end of a
125 lever 68 fulcrumed at 69. The lower end
of the lever 68 is connected with one end
of a connecting rod 70, which is connected
at its other end with a crank pin 71 driven
by a gear 73, which receives its actuation
130 in any convenient manner from the main

shaft 74 of the flying machine. The rotation of the crank pin 71 causes the lever 68 to oscillate constantly; and while the pawl 64 is normally held from engagement with the rack 65, the reciprocations of the pawl 64 are not communicated to the shaft 34, as shown in Fig. 1. When, however, the flying machine reaches a predetermined height or plane of travel, and the pawls are brought into engagement with the rack 65, the reciprocations of the actuating pawl 64 cause the shaft 34 to be racked to the right. The means for drawing the pawls 63 and 64 into engagement with the rack 65 comprises two solenoids 75 and 76 conveniently supported from the bracket 35. These solenoids act upon armatures 77 carried by the pawls. The solenoids 75 and 76 are energized by a battery 79 when the indicating needle 80 of a barometer 81 indicates that the flying machine has reached a certain height. When the machine has reached this height, the end 83 of the needle will be in contact with the terminal 84 of a circuit 85 and thereby close the circuit, permitting the battery 79 to energize the solenoids to draw the pawls into engagement with the rack 65. As the roll 29 travels up the incline 60 of the cam 33, owing to the movement of the shaft 34 by the rack and pawl device, the bellcrank lever 26 is turned in a clockwise direction to move the collar 21 to the right, viewing Fig. 1, so as thereby to impart a movement to the lever 15 in a contra-clockwise direction to cause the centering cam 5 to move forwardly and thereby bring about a lessening of the angle of incidence of the wing planes. As before pointed out, when the roll 29 rests upon the surface 88 of the cam 33, which it does when the flying machine is traveling along the ground, the wing planes are substantially horizontal, so that they have no lifting effect upon the machine. The surface 61 is made slightly lower than the surface 88, so that when the roll 29 rests upon the surface 61, the wing planes are held at just that angle of incidence which is necessary to maintain the machine at a constant level when it is flying at a certain speed. If at any time the machine should descend, the heavier atmosphere in the lower regions will of course compel the retrograde movement of the indicating needle 80, thereby breaking the contact between the part 83 of the needle and the terminal 84. The solenoids no longer receiving energy from the battery will permit the springs 66 and 67 to disengage the pawls 63 and 64 from the rack 65; thereupon a spring 90 carried on the extreme left-hand end of the shaft 34 acts to move the shaft to the left to permit the roll 29 to descend into the depression 32; whereupon the wing planes are again tilted to cause the machine to ascend. It will be observed that the space separating the collar 91 from the end 92 of the bracket 35 equals the distance from the center of the depression 32 to the center of the roll 29, so that when the roll 29 occupies the depression 32, the collar 91 will take lightly against the end 92 of the bracket 35. Any further movement of the shaft 34 to the right will then compress the spring 90 so that it will tend to move the shaft 34 to the left to bring the roll 29 opposite the center of the depression 32. When the shaft 34 has been racked to the right by the pawl 64, the pawl 64 reciprocates idly on the surface 94.

If at any time the fore and aft equilibrium of the flying machine is overcome by an excess vertical pressure on either the front or rear portions thereof, the machine will be automatically restored to the plane upon which it was flying, by means of a float contrivance constructed and arranged to act upon the roll 7. This float contrivance comprises two floats 95 and 96 secured to the shaft 10. The floats are located in a tank 97 sustained upon the framework 11. The tank 97 contains a sufficient quantity of oil 98, or other liquid, to normally maintain the floats, the shaft 10 and the parts connected with it, in the positions shown in Fig. 2. If now the machine tips rearwardly, the liquid will travel up about the float 96 and thereby exert a pressure upon it to turn the shaft 10 in a counter-clockwise direction. This turning of the shaft 10 will cause the slot 18 to depress the pin 16 and so turn the lever 15 in a counter-clockwise direction to move the centering cam forward and thereby decrease the angle of incidence of the wing planes. This will result in an increase in the speed of the machine at the same time causing the forward part of the machine to descend, and thereby tends to right or restore the equilibrium of the machine. This action will continue until the machine is restored to the plane upon which it was proceeding when the disturbing force encountered it. As the machine is righted, the float 96 will descend, turning the shaft 10 in a clockwise direction, which will result in the centering cam 5 moving rearwardly to restore the wing planes to their former angle of incidence. If an excess vertical pressure on the forward part of the machine depresses the forward part thereof, then the float mechanism will act to cause the wing planes to present a greater angle of incidence to the atmosphere until the machine is again righted. The movements of the parts during this latter process will of course be the reverse of what they were when the rear end of the machine was depressed. The action of the float mechanism on the wing planes is substantially the same as the action of a similar float mechanism on the wing plates of the said Patent No. 1,200,288.

The steering apparatus of the present invention has been described as being applied specifically to a flying machine of a particular type, in which the vertical flight of the machine is controlled by tilting the sustaining wing planes. It will be understood, however, that the steering apparatus of the present invention is not restricted to application to any particular type of flying machine or aeroplane, nor even to an aerial vehicle, inasmuch as it may be applied to any type of flying machine, and also to marine vehicles. In this respect it will be understood that the term "wing planes" is generic, inasmuch as it includes any guiding device used for changing the vertical travel of the vehicle.

Having thus described the invention, what is claimed as new is:

- 20 1. An automatic steering apparatus for vehicles having, in combination, a guiding-device controlling means, means operative when the vehicle has reached a predetermined speed on one level to move the controlling means to cause the vehicle to leave said level, and means operating on the controlling means when the vehicle has attained another predetermined level to maintain the vehicle on that level.
- 25 2. An automatic steering apparatus for vehicles having, in combination, a guiding-device controlling means, means including a centrifugal device for moving the controlling means when the vehicle has reached a predetermined speed on one plane of travel to cause the vehicle to rise to a predetermined height, and means for maintaining the vehicle on the plane of travel at the predetermined height.
- 30 3. An automatic steering apparatus for vehicles having, in combination, a guiding-device controlling means, means including a centrifugal device for moving the controlling means when the vehicle has reached a predetermined speed on one plane of travel to cause the vehicle to rise, and means including a barometer for acting on the controlling means to maintain the vehicle on the plane of travel at the predetermined height.
- 35 4. An automatic steering apparatus for vehicles having, in combination, a guiding-device controlling means, a cam, connections between the controlling means and the cam, automatically acting means for moving the cam to cause the vehicle to rise, and additional means operative when the vehicle has reached a predetermined height for moving the cam to cause the vehicle to be maintained on the plane of travel at the predetermined height.
- 40 5. An automatic steering apparatus for vehicles having, in combination, a guiding-device controlling means, a cam, connections between the controlling means and the cam, a centrifugal device for moving the
- cam to cause the vehicle to rise when it has reached a predetermined speed on one plane of travel, and means operative when the vehicle has risen to a predetermined height to move the cam to cause the vehicle to be maintained on the plane of travel at the predetermined height.
- 45 6. An automatic steering apparatus for vehicles having, in combination, a guiding-device controlling means, a cam, connections between the controlling means and the cam, means for moving the cam to cause the vehicle to rise, and a rack and pawl device controlled by a barometer for moving the cam when the vehicle has reached a predetermined height to cause the vehicle to be maintained on the plane of travel at the predetermined height.
- 50 7. An automatic steering apparatus having, in combination, a guiding-device controlling means, means including a centrifugal device for moving the controlling means to cause the vehicle to rise when the vehicle has reached a predetermined speed on one plane of travel, means contacting with the ground to actuate the centrifugal device, and means operative when the vehicle has risen to a predetermined height for acting on the controlling means to cause the vehicle to be maintained on the plane of travel at the predetermined height.
- 55 8. An automatic steering apparatus for vehicles having, in combination, a guiding-device controlling means, and means for controlling said controlling means comprising a shaft, a member loosely mounted thereon having a hub provided with a projecting pin, a sleeve slidably mounted on the shaft and rotatably fixed with respect thereto having a cam slot for receiving the projecting pin, and means for sliding the sleeve upon the shaft.
- 60 9. An automatic steering apparatus for vehicles having, in combination, a guiding-device controlling means, and means for operating on the controlling means to maintain the vehicle on a predetermined level comprising a rack, a detent pawl for preventing retrograde movement of the rack, a pivotally mounted lever, an actuating pawl for the rack pivoted upon the lever, means for normally maintaining the actuating pawl out of engagement with rack, means for actuating the actuating pawl into engagement with the rack, and means for oscillating the lever.
- 65 10. An automatic steering apparatus for vehicles having, in combination, a guiding-device controlling means, means for moving the controlling means when the vehicle has reached a predetermined speed on one plane of travel to cause the vehicle to rise to a predetermined height, and means for maintaining the vehicle on the plane of travel at the predetermined height.

11. An automatic steering apparatus for vehicles having, in combination, a horizontal guiding-device, controlling means therefor, a cam, connections between the controlling means and the cam, means for moving the cam to cause the vehicle to move from one plane to another, and additional means operative when the vehicle has reached a predetermined height for moving the cam to cause the vehicle to be maintained on the plane of travel at the predetermined height.
12. An automatic steering apparatus for vehicles, having in combination, a horizontal guiding-device, controlling means therefor, a cam, connections between the controlling means and the cam, and means operative when the vehicle has reached a predetermined height for moving the cam to cause the vehicle to be maintained on the plane of travel at the predetermined height.
13. An automatic steering apparatus for vehicles having, in combination, a guiding-device controlling means, mechanism for actuating said means, means for moving said mechanism to cause the vehicle to move from one plane to a predetermined plane of travel, and additional means for moving said mechanism to cause the vehicle to be maintained on said predetermined plane of travel.

ERASTUS E. WINKLEY.
